(57) **CLAIM**

The ornamental design for a cabinet column, as shown and described.

DESCRIPTION

FIG. 1 is a front, top perspective view of a cabinet column, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an environmental of use.

The evenly spaced broken lines depicted on the cabinet column define the bounds of the claimed design and form no part thereof. The evenly spaced broken lines in FIG. 9 depicting a cabinet, are for the additional purpose of showing environmental structure, and form no part of the claimed design. The cabinet column is shown with a symbolic break. The appearance of any portion of the cabinet column between the break lines forms no part of the claimed design.
